(57) **CLAIM**

The ornamental design for a sign for shelf, substantially as shown and described.

DESCRIPTION

FIG. 1 is a front view according to a first embodiment of the sign for a shelf in an unfolded state.

FIG. 2 is a rear view of the sign for a shelf of FIG. 1.

FIG. 3 a right side view of the sign for a shelf of FIG. 1 in a folded state.

FIG. 4 a left side view of the sign for a shelf of FIG. 1 in a folded state.

FIG. 5 a front perspective view of the sign for a shelf of FIG. 1 in a folded state.

FIG. 6 is a front view of the sign for a shelf of FIG. 1 in an unfolded state showing environment.

FIG. 7 is a front perspective view of the sign for a shelf of FIG. 1 in a folded state showing environment.

FIG. 8 is a front view according to a second embodiment of the sign for a shelf in an unfolded state.

FIG. 9 is a rear view of the sign for a shelf of FIG. 8.

FIG. 10 a right side view of the sign for a shelf of FIG. 8 in a folded state.

FIG. 11 a left side view of the sign for a shelf of FIG. 8 in a folded state.

FIG. 12 a front perspective view of the sign for a shelf of FIG. 8 in a folded state.

FIG. 13 is a front view of the sign for a shelf of FIG. 8 in an unfolded state showing environment; and,

FIG. 14 is a front perspective view of the sign for a shelf of FIG. 8 in a folded state showing environment.

The portions of FIGS. 6, 7, 13, and 14 shown in broken lines illustrate environment and do not form part of the claimed design.

1 Claim, 8 Drawing Sheets
